UNITED STATES PATENT OFFICE.

HARRY L. TANNER, OF BROOKLYN, NEW YORK, ASSIGNOR TO THE TANNER ENGINEERING COMPANY, INC.

POSITION INDICATOR.

Application filed March 24, 1920. Serial No. 368,412.

This invention relates to electrical position indicators used to signal or transmit from one point to another the position of some object such as the rudder of a ship, the 5 level of water in a reservoir, the reading of a measuring instrument, or the like.

The purpose of the invention is to reduce as far as possible both the number of moving parts and the number of transmission wires 10 in such an instrument. In my prior Patent No. 1,320,807, for indicator, dated November 4, 1919, and in my copending application No. 238,747, for telemetric devices, filed June 7, 1918, (now Patent No. 1,350,345, dated August 24, 1920), I disclose a means for securing a plurality of indications with a greatly less number of wires than had heretofore been used in systems of this character. By this 15 invention I improve on my previous inventions by eliminating a large number of moving parts and using only one index or movable indicator. By this improvement it is possible to utilize my invention for indicating an almost unlimited number of separate 20 positions or for operating a marker for a recording instrument, or the like, and also for operating the pen of a recording instrument.

Other objects of the invention will become apparent as the description proceeds.

Referring to the drawings in which what I now consider the preferred forms of my invention are shown:

Fig. 1 is a diagrammatic view of one form of apparatus.

Fig. 2 is a similar diagrammatic view of another form.

Fig. 3 is a fragmentary detail view looking in the direction of the axis 31-32 from the left towards the right in Fig. 2 and with the arm 36 uppermost, the bearings and certain other parts being omitted for clarity in illustration.

For the sake of illustration I have chosen an indicator having only four electromagnetic actuating elements, from which it follows that the indicator will have 2⁴-1 or 15 positions from the principles outlined in my prior patent and patent application. Furthermore, for the sake of simplicity, the showing is diagrammatic. 1 represents an armature pivoted at 2 and normally biased to turn in the direction of the arrow by means of a spring 3. Said armature is preferably provided with a plurality of cores 4 and 5 adapted to cooperate with solenoids 6

and 7. Said armature has four positions—first, when neither solenoid is excited (as shown in dotted lines); second, when solenoid 6 is excited centralizing core 4 therein; third, when both solenoids 6 and 7 are excited placing the armature in a vertical position; and fourth when solenoid 7 alone is excited which centralizes core 5 therein. The full line position is the third position.

On the opposite end of armature 1 is a pin 8 extending within a U or V shaped slot 9 in lever 10. Said lever is shown as pivoted at 11 and is normally biased to turn in the direction of the arrow by means of spring 12 thereby holding the lower edge of slot 9 against pin 8. A solenoid 13 when excited tends to draw armature 14 clockwise until the upper edge of said slot strikes pin 8. Obviously said lever will have four positions when solenoid 13 is deenergized, one for each position of lever 1, and four other positions if slot 9 is correctly designed when the solenoid is excited.

At another point in said lever, preferably adjacent its opposite end is another U or V shaped slot 15, into which a pin 16 on pointer or other index 17 projects. Said pointer is shown as pivoted at 18 and is normally biased to turn in the direction of the arrow by means of spring 19. A fourth solenoid 20, when excited, will draw armature 21 secured to lever 17 clockwise. It will, therefore, be readily apparent that, with the slot properly designed pointer 17 will have eight positions with solenoid 20 unexcited and eight positions with the same excited, or sixteen in all, if none overlap, and counting the position of rest or fifteen actual positions. Preferably the walls of the slots are curved or spiraled so that the graduations on the scale will be of uniform spacing.

The transmitter for actuating the indicator comprises four contacts of any suitable form and diagrammatically represented in Fig. 1 as spring fingers 22, 23, 24, and 25 opened and closed by means of cams 26 so designed as to close the contacts preferably in the following sequence: (6), (6 and 7), (7), (7 and 13), (6, 7 and 13), (6 and 13), (13), (13 and 20), (6, 13 and 20), (6, 7, 13 and 20), (7, 13 and 20), (7 and 20), (6, 7 and 20), (6 and 20), (20). It will be understood that the cams are mounted on the same shaft so as to be turned together when the sending instrument is rotated.

The principles outlined above are obviously capable of many modifications. Thus from the above description it will be obvious how an indicator would be constructed for 5 simply six or seven steps, or for a much greater number than fifteen by duplicating the slotted lever 10.

In Fig. 2 I have shown several modifications in structure of my invention and also 10 show how it may be employed as a recording meter.

According to this modification, the windings 6' and 7' are mounted side by side and have a common core 25 mounted on a shaft 15 26 slidably mounted in bearings 27 and 28. Said core is normally pulled to the right by spring 29 but will move in successive steps to the left by the excitation of windings 6', 6' and 7' (together) and 7' in the order 20 named. Shaft 26 is provided with a pin 8' working in a V-shaped slot 9' in a member 30. Said member is pivoted on pivot pins 31 and 32 and the said member is biased in the direction of the arrow shown in Fig. 3. 25 The core 34 of solenoid 13' is secured to said member 30 by link 35 so that upon excitation of the solenoid, said member is rotated upwardly, if pin 8' will permit. As before member 30 is provided with a second V-shaped slot 15', a pin 16' on lever 36 working therein. The fourth solenoid 20' may operate as before to turn lever 36 clockwise against the action of spring 19'. Adjacent its end said lever is shown as provided with 30 a slot 37. A rod 38 slidably mounted as between rollers 39 and 40 has a pin 41 taking in said slot so that a longitudinal movement is imparted to said rod upon turning of the lever. Any suitable tracing means such as 35 pen 42 is secured to the rod so as to trace a record 43 on chart 44 as it is moved in the direction of the arrow by clockwork (not shown).

In accordance with the provisions of the 40 patent statutes, I have herein described the principle of operation of my invention, together with the apparatus, which I now consider to represent the best embodiment thereof, but I desire to have it understood 45 that the apparatus shown is only illustrative and that the invention can be carried out by other means. Also, while it is designed to use the various features and elements in the combination and relations described, some 50 of these may be altered and others omitted without interfering with the more general results outlined, and the invention extends to such use.

Having described my invention, what I 55 claim and desire to secure by Letters Patent is:

1. In an indicator, a movable index, means for moving the same in at least two directions, and movable means for arresting such movement of said index in one of said

two directions in a plurality of different positions and for arresting such movement of said index in the other of said two directions in a plurality of different positions.

2. In an indicator, a movable index, 70 means for moving the same in a plurality of directions, a member movable in two directions for arresting such movement, and a third movable member for arresting the movements of the second member in each 75 direction.

3. In an electric indicator, a movable index, a plurality of electromagnetic devices having armatures biased to unattracted position, means for exciting said devices in a 80 predetermined sequence, and means responsive to such excitation for moving said index to a number of different positions equal to the maximum combinations of the number of said devices, said last named means including an operative connection between one of said devices and said index, and a 85 movable member also operatively connected to said index and to the other devices for limiting movement of said index by one of said devices.

4. In an electrical indicator, a member normally biased to move in one direction, electromagnetic means for causing movement in a different direction, a second electromagnetic means having a plurality of positions for limiting the movement of said member in each direction, an index, electromagnetic means for moving the same in two directions, and means interconnecting said index and member whereby said index has a possible number of positions as great as the possible number of combinations of the number of electromagnetic means.

5. In an indicator, a movable index, means 105 for moving the same in a plurality of directions, and movable means for arresting such movement in a plurality of different positions comprising a pivoted member movable in opposite directions, means for moving the same in both directions and movable means for arresting said last named movement in a plurality of positions.

6. In an indicator, in combination, a movable member, means for moving said member to any one of a plurality of positions, a second movable member, means for moving said second member in either of opposite directions, mechanism interconnecting said first and second members for limiting the 115 movement of said second member to substantially double the number of positions of said first member, a third movable member, means for moving said third member in either of opposite directions, and mechanism interconnecting said second and third members for limiting the movement of said third member to substantially double the 120 number of positions of said second member.

7. A combination as set forth in claim 6 130

- in which selective means are provided for individually or jointly controlling the means for moving the movable members.
8. In an indicator, a movable index, means for moving the same in a plurality of directions, a member movable in two directions for arresting such movement, a third movable member for arresting the movements of the second member in each direction, and means for moving each of said members individually and in groups in a predetermined sequence.
9. In a position indicator, a step-by-step electromagnetic device having an armature with a plurality of positions, a second electromagnetic device having an armature with two directions of movement, means connecting said devices so that said second device may be caused to assume double the positions of said first device according to whether one or another or a combination of said electromagnetic device is energized, and means for energizing said electromagnetic devices singly and jointly.
10. In combination, a movable index, means comprising an electromagnet for moving said index in opposite directions, movable means for arresting such movement of said index in either direction in a plurality of different positions, a plurality of electromagnets for controlling said movable means, and selective means for energizing one or another or groups of said electromagnets in a predetermined sequence.
11. In a position indicator, a movable member, a movable indication-producing device controlled by said member, means comprising at least three electromagnets and operative connections between the same and said member for causing said member to assume various positions of a number of different positions equal to the maximum number of combinations of the total number of electromagnets when the latter are energized in various combinations, and means including contacts and connections controlling said electromagnets for causing said member to assume its various positions by changing the circuit of not more than one electromagnet at a time when passing from any of said positions to any next adjacent position.
12. In an indicator, a movable index, means for moving the same in at least two directions, movable means for arresting such movement of said index in one of said two directions in a plurality of different indicating positions and for arresting such movement of said index in the other of said two directions in a plurality of different indicating positions, and electromagnetic means for controlling said movable means.
13. In an indicator, a movable index, means for moving said index in at least two directions, a movable device for arresting such movement of said index in one of said two directions in a plurality of different positions and for arresting such movement of said index in the other of said two directions in a plurality of different positions, and means for controlling the position of said movable device.
14. In combination, a movable index, means comprising an electromagnet for moving said index in opposite directions, movable means for arresting such movement of said index in either direction in a plurality of different positions, a plurality of electromagnets for controlling said movable means, and means for energizing said electromagnets one, two, and three at a time in a predetermined sequence.
15. In an indicator, a movable index, means for moving said index in at least two directions, movable means for arresting such movement of said index in one of said two directions in a plurality of different indicating positions and for arresting such movement of said index in the other of said two directions in a plurality of different indicating positions, and means including electromagnets controlling said first and second mentioned means for causing said indicator to assume a number of operated positions in excess of the number of electromagnets.

In testimony whereof I have affixed my signature.

HARRY L. TANNER.
